(57) **CLAIM**

I claim the ornamental design for a beverage container top, as shown and described.

DESCRIPTION

FIG. 1 is a front perspective view of the beverage container top, showing my new design;

FIG. 2 is an enlarged side perspective view thereof;

FIG. 3 is a top view thereof;

FIG. 4 is an enlarged perspective view thereof;

FIG. 5 is an enlarged left perspective side view thereof;

FIG. 6 is an enlarged right perspective side view thereof;

FIG. 7 is a reduced scale front elevational view thereof;

FIG. 8 is a reduced scale right side elevational view thereof;

and,

FIG. 9 is a reduced scale left side elevational view thereof.
